Fig. 1

Fig. 2

Fig. 3

Figure 1 is a front elevational view of a pillow toy embodying my new design;

Figure 2 is a side elevation view thereof, and

Figure 3 is a rear elevational of the pillow toy.

The drawing is lined for color-contrast.

The design is characterized by the arcuate stitching, extending in spaced relation to the arcuate top edge of the pillow toy to provide opposed convex-concave faces on the toy, together with, the imprinted face being offset toward the bottom of the pillow toy, and the difference in thickness of the non-circular face and handle portions of the pillow toy, all as shown.

I claim:

The ornamental design for a pillow toy, as shown and described.
